UNITED STATES PATENT OFFICE.

PAUL S. LUTTRELL, OF OAKLAND, AND PAUL C. ROSKE, OF SAN FRANCISCO, CALIFORNIA, ASSIGNORS TO AMERICAN CLOCK CORPORATION, OF OAKLAND, CALIFORNIA, A CORPORATION OF CALIFORNIA.

ALARM SETTING AND ACTUATING MECHANISM FOR CLOCKS.

Application filed December 21, 1922. Serial No. 608,197.

To all whom it may concern:

Be it known that we, PAUL S. LUTTRELL and PAUL C. ROSKE, citizens of the United States, residing at Oakland, county of Alameda, and at the city and county of San Francisco, and State of California, respectively, have invented new and useful Improvements in an Alarm Setting and Actuating Mechanism for Clocks, of which 10 the following is a specification.

This invention relates to an alarm setting and actuating mechanism for clocks and like mechanisms.

Most clocks in use today, and particularly 15 those employing an alarm mechanism, are more or less unsatisfactory as it is difficult to accurately set the alarm mechanism to sound at a predetermined time or hour, this being particularly true if the time desired is a few minutes before or after a given hour. Another disadvantage is that most alarm mechanisms cannot be reset and re-wound for the same time within two or three hours of the last alarm. The object 20 of the present invention is to generally improve and simplify mechanisms of the character described; to provide an alarm setting and actuating mechanism which may be accurately set to the time desired and which 25 may also be set to sound an alarm on any minute or half minute graduation, and further to provide a mechanism of this character which may be immediately re-wound and re-set for the same time, or at least within 30 eleven hours and fifty-seven minutes 35 thereof, or which may be re-set for the same time, to-wit, twelve hours thereafter, the moment a time period of three minutes has elapsed.

The invention further embodies an interlocking mechanism, to-wit, an alarm releasing lever and an alarm winding key, the alarm releasing lever being so positioned 40 that it engages the winding key and prevents rotation thereof, this being of importance as it necessarily forces the person desiring to set and wind the alarm first to swing the releasing lever to On position before the winding mechanism may be 45 wound by the winding key. It often happens where ordinary alarm clocks are employed that a person will wind the alarm and also set the alarm, but will neglect to release the alarm. If this is the case, it is 50

obvious that no alarm will be sounded 55 at the time desired and the whole mechanism for this reason proves a failure. In the present instance no such a mistake can be made as setting of the alarm must first take place, secondly the alarm releasing 60 lever must be moved to On position, and third, the alarm mechanism must be wound by means of the winding key, but as the alarm cannot be wound before the releasing lever is moved to On position, it is obvious 65 that the proper coordination is obtained between the different parts of the mechanism.

Other objects will hereinafter appear.

One form which our invention may assume is exemplified in the following description and illustrated in the accompanying drawings, in which—

Fig. 1 is a front view of the clock.

Fig. 2 is a rear view of the same.

Fig. 3 is another rear view of the clock 75 partially in section showing the rear cover section removed.

Fig. 4 is a general view of the clock mechanism, said view also showing a portion of the alarm setting and actuating mechanism. 80

Fig. 5 is a bottom view of the clock.

Fig. 6 is a central, vertical cross section taken through the clock and showing the major portion of the mechanism employed.

Referring to the drawings in detail, and 85 particularly to Figs. 3, 4 and 6, A indicates the main housing of the clock, and B the frame plates by which the clock mechanism is supported. These frame plates are interspaced, as shown in Fig. 6, and are secured to the rear cover section C of the clock in any suitable manner. The usual gear train is employed, to-wit, a main spring D, a first wheel or gear 1, a second wheel 2, a third wheel 3, and a fourth wheel 4. This 90 direction gear train drives the escapement mechanism, generally indicated at 5, and a balance wheel 6, which is actuated thereby. This part of the mechanism is constructed in the usual manner, but as it cooperates 95 with the remaining mechanism, hereinafter to be described, a brief description has been rendered.

The clock illustrated is provided with the usual graduated dial 7, see Figs. 1 and 6, an hour hand 8, and a minute hand 9, the minute hand being secured to the usual form of spindle 10, which is driven by the second

wheel, and the hour hand 8 is similarly driven in the usual manner by a dial gear train, such as indicated at 11. The clock is also provided with the usual form of alarm mechanism, to-wit, a spring E, a pair of gears 12 and 13 driven thereby, and a star gear 14, which actuates the alarm pallet 15 and the hammer 16 actuated thereby.

The invention involved in the present instance is the provision of a novel form of alarm winding, setting and actuating mechanism. This mechanism consists of a spindle 17, journaled within the main frame and disposed at right angles to the main spindle 10, that is, it is vertically disposed in the casing and projects through the bottom portion thereof. Suitably secured to this spindle is a minute hand 18 and a setting screw 19, and secured to a sleeve journaled exterior of the spindle 17, as at 20, is an hour hand 21. The sleeve 20 and the spindle 17 are connected by a dial train similar to that illustrated at 11, that is one revolution of spindle 17 will transmit one-twelfth of a revolution to the sleeve and the hour hand carried thereby, and the gear trains employed are therefore similar to the gear train referred to and generally indicated at 22.

30 The spindle 17 forms two functions, first that of actuating the minute or hour hands indicated at 18 and 21, respectively, and secondly that of imparting movement to the alarm locking and releasing mechanism, 35 which will hereinafter be referred to as the alarm actuating mechanism. This mechanism consists of two disks, one to be known as the minute disk and the other as the hour disk, the minute disk being indicated at 23, and the hour disk at 24. The minute disk rotates in unison with the main spindle 10 and therefore makes one revolution during each hour. The hour disk 24 is intermittently driven by the minute disk and makes one-twelfth of a revolution during each hour. Both disks serve a common function, to-wit, either that of locking the alarm mechanism, or conversely, that of releasing the alarm mechanism. The minute disk is 40 ordinarily driven by the main spindle 10 through means of a ratchet gear 25 and a pair of pawls 26, but it may be manually rotated by the spindle 17 through a second ratchet gear 27 and pawls 28. The ratchet gear 27 is freely turnable on the spindle, while the ratchet gear 25 is keyed or pinned thereto as indicated at 29. It may furthermore be stated that the pawls 26 and 28 are secured to opposite sides of the minute disk and that they extend in the same direction with relation to each other. Also, that each ratchet gear contains sixty teeth and that these teeth extend in the same direction and are staggered with relation to each other. 45 This is of importance as it permits the alarm

mechanism to be set for full or one-half minutes as desired.

The ratchet gear 27 is carried by a sleeve 30, which is freely turnable on the spindle and this sleeve in turn carries a pin gear 31, which intermeshes with a similar pin gear 32 secured on the spindle 17. Thus, if spindle 17 is rotated by means of the setting screw 19, movement is transmitted through the gears 31 and 32 to rotate the sleeve 30 and the ratchet gear 27, and when so rotated pawls 28 are engaged and movement is consequently imparted to rotate the minute disk. Pawls 26 will in that instance ride freely over the ratchet gear 25 as the teeth and pawls are reversed to the pawls and teeth of the ratchet gear 27. Therefore, no interference will be encountered between the ratchet gears. It may further be stated that the ratchet gear 27 can only be rotated in one direction as a ratchet 33 with a cooperating pawl 28 is employed to prevent reverse rotation, the gear 33 being secured on the spindle 17 as shown in Fig. 6. The minute disk, as previously stated, is normally rotated in unison with the spindle 10 through means of the ratchet gear 25 and pawls 26, that is during the normal operation of the clock mechanism the spindle 10 is driven by the clock mechanism, but it may also be manually rotated by means of the spindle as the spindle itself may be manually rotated through means of a setting screw, such as indicated at 35, see Fig. 6.

Movement is transmitted from the minute disk to intermittently rotate the hour disk 24 one-twelfth of a revolution during one revolution of the minute disk. This is accomplished by securing the hour disk on a spindle 36 and by also securing a star gear 37 on the same spindle. There are twelve teeth on the star gear and these teeth are intermittently engaged by a pin 38 secured on the minute disk 23. It will also be noted, by referring to Fig. 3, that one of the teeth of the star gear 37 is slightly enlarged, as indicated at 39. This tooth is so positioned that it is engaged by the pin 38 when the alarm mechanism is released. The minute disk is provided with a notched portion 40, see Fig. 3, and the hour disk is similarly notched as indicated at 41. These notched portions of the respective disks register with the alarm hammer, or rather an extension thereof, when the alarm mechanism is to be released, and the extension of the alarm hammer is thus permitted to freely oscillate when the notched portions of the respective disks move into register therewith. The extension of the alarm hammer is generally indicated at F. One arm of the extension, indicated at 42, engages the periphery of the minute disk, and the other portion of the extension engages the periphery of the hour disk 24. How-

ever, when the notches in the respective disks align, as shown in Fig. 3, the extension F is released and free oscillation is permitted and the alarm mechanism will 5 sound, that is the hammer strikes a bell, as indicated at 44, and the sound produced may be increased or damped as desired by means of a damper lever as indicated at 45.

The star gear 37 and the hour disk 24 10 are both secured to a common sleeve 37^a which in turn is freely turnable on the stationary spindle or stud shaft 36. It was previously stated that the star wheel and the disk 24 were turned in unison by means 15 of a pin 38 on the minute disk and that one-twelfth of a revolution would be imparted during each engagement. If the sleeve 37^a carrying the star wheel and hour disk is freely turnable on the stud shaft or 20 spindle 36, it is obvious that means must be provided for preventing more than one-twelfth of a revolution. For this reason a pawl and ratchet are provided. The ratchet indicated at 36^a is secured to the spindle 25 36, while the pawl 24^a is pivotally secured to the hour disk. The pawl rides freely over the ratchet during each one-twelfth of a revolution of the hour disk and the star wheel, and it thus secures the hour disk 30 and star wheel against further movement and also against accidental reverse movement. The pawl and ratchet, in other words, act as a frictional resistance which will permit a member to rotate, but which 35 will insure an instantaneous stop when the member imparting the rotary movement is released. In other words, while the pawl and ratchet are shown to frictionally resist the movement of the hour disk and to instantaneously stop it, any other friction device 40 might be employed.

The operation of the device will be as follows:

If it is desired to set the alarm for a 45 given hour or for any intermediate time period up to a half minute, it will only be necessary to grasp the set screw 19 and turn it in the direction of the arrow as indicated in Fig. 5. The member 19 is 50 secured to the spindle 17 and the minute hand 18 is also secured thereto. The dial train indicated at 22 turns the hour hand 21, and turning movement is therefore continued until the desired time is registered 55 on the dial shown at 50, see Fig. 5. The minute disk and the hour disk are simultaneously advanced due to the movement transmitted from the spindle 17, that is the minute disk is rotated by means of the 60 ratchet gear 27 and the pawls 28 through means of the pin gears 31 and 32, and each revolution of the minute disk is transmitted to intermittently rotate the hour disk indicated at 24. The clock mechanism 65 will thereafter advance the disks as pre-

viously described through means of the ratchet gear 25 and pawls 26, and the alarm will be released when the large tooth 39 of the star gear is engaged, that is the notches 40 and 41 will at this time register with the lever F and the lever is therefore released and will then oscillate as the alarm pallet will then be free to operate. It was previously stated that the tooth 39 was larger than the remaining 70 teeth. This is important as it causes an increased movement or advance of the hour disk 24, the movement being sufficient to advance the notch 41 to a point where it will again lock the lever F the moment 75 the alarm has sounded. This is obviously an advantage as it permits immediate re-winding and re-setting of the alarm mechanism if desired.

In conjunction with this matter another 80 important feature is provided, that is the alarm mechanism is provided with a manual release lever 51, see Fig. 4, which is swung into or out of engagement with the hammer 16 by means of an exterior release lever 52. 85 This lever is so arranged that when swung to Off position, as shown in Fig. 2, it lies directly in the path of the alarm winding key indicated at 53. This key cannot be turned when the releasing lever is swung 90 to Off position, and it is therefore necessary to release the alarm mechanism if it is desired to re-wind the same. Practically all alarm clocks can be re-wound regardless 95 of the position of the release lever and as 100 this is the case it often happens that a person will re-wind the alarm and also set the alarm, but will forget or neglect to release the lever 52. This cannot happen 105 in the present instance as the release lever must be swung to release or On position 110 before it is possible to re-wind the alarm and a person is therefore forced or positively reminded of the fact that the release lever must be swung to release position before the alarm can be re-wound. The 115 alarm setting mechanism is operable independently of this portion of the mechanism, but will of course not operate unless the alarm spring is wound.

From the foregoing description it can be seen, first that the alarm mechanism may be accurately set to any given hour or to any intermediate minute or one-half minute graduation, and that the time desired will 120 be visibly indicated by the alarm dial shown at 50, in Fig. 5, this alarm dial being formed on the bottom of the clock casing. Second, that the winding mechanism cannot be re-wound without releasing the alarm releasing 125 lever. Third, that the automatic release of the alarm mechanism by the main clock mechanism is controlled by the minute and hour disks, and that these disks will not release the alarm mechanism until the 130

notches 40 and 41 register as shown in Fig. 3. Fourth, that an added or increased turning movement is transmitted to the hour disk during the releasing period by 5 enlarging one of the teeth of the star gear by which it is actuated, thereby automatically locking the alarm mechanism the moment it has completed its operation, and as such is the case it permits immediate re- 10 setting of the alarm for another time period. It also permits immediate re-setting of the alarm for an advanced period of eleven hours and fifty-seven minutes. And fifth, that no part of the clock mechanism can be 15 reversed as ratchet gears and pawls are employed to prevent reverse movement.

Having thus described our invention, what we claim and desire to secure by Letters Patent is—

- 20 1. In a mechanism of the character described, the combination with the minute hand spindle, of a minute disk adapted to be rotated in unison therewith, an hour disk adapted to be intermittently rotated by the 25 minute disk, and means actuated by both disks to release or lock an alarm pallet.
2. In a mechanism of the character described, the combination with the minute hand spindle, of a minute disk supported by the 30 spindle and adapted to be rotated in unison with the spindle, an hour disk mounted adjacent the minute disk, means for transmitting a twelfth of a revolution to the hour disk during one revolution of the minute disk, and means cooperating with said disks 35 for slightly increasing the rotary movement of the hour disk once during a complete revolution thereof.
3. In a mechanism of the character described, the combination with the minute hand spindle, of a minute disk freely turnable on the spindle, means carried by the spindle for rotating the disk in unison with the spindle, and means for manually rotating the minute disk independently of the 40 spindle.
4. In a mechanism of the character described, the combination with the minute hand spindle, of a minute disk freely turnable on the spindle, a ratchet gear secured to the spindle, pawls pivotally mounted on the minute disk and engaging said ratchet gear, said pawls adapted to form a driving connection between the minute disk and the 45 ratchet gear to rotate the minute disk in unison with the spindle, a second ratchet gear freely turnable on the spindle, pawls pivotally secured to the minute disk and engaging said ratchet gear, the pawls and the teeth of said last named ratchet gear extending in the same direction as the pawls and teeth of the first named ratchet gear, and means for manually rotating the second named ratchet gear.
5. In a mechanism of the character de- 50 scribed, the combination with the minute hand spindle, of a minute disk freely turnable on the spindle, a ratchet gear secured to the spindle, pawls pivotally mounted on the minute disk and engaging said ratchet gear, said pawls adapted to form a driving connection between the minute disk and the ratchet gear to rotate the minute disk in unison with the spindle, a second ratchet gear freely turnable on the spindle, pawls pivotally secured to the minute disk and engaging said ratchet gear, the pawls and the teeth of the last named ratchet gear extending in the same direction as the pawls and teeth of the first named ratchet gear, and means for manually rotating the second named ratchet gear, said means comprising a second spindle, a gear train forming a connection between said spindle and the second named ratchet gear, a minute hand secured to said second named spindle, an alarm dial with which said minute hand cooperates, a sleeve freely turnable on the second named spindle, an hour hand secured thereto, and a dial gear train forming a connection between the second named spindle and the sleeve turnably mounted thereon.
6. In a mechanism of the character described, a main minute hand spindle, a minute disk freely turnable thereon, means for automatically rotating the minute disk in unison with the spindle, means for manually rotating the disk independently of the spindle, an hour disk positioned adjacent the minute disk, a star gear cooperating with the hour disk and having twelve teeth formed thereon, and a pin on the minute disk adapted to successively engage the teeth on the star gear and thereby impart a twelfth of a revolution to the hour disk during each revolution of the minute disk.
7. In a mechanism of the character described, a main minute hand spindle, a minute disk freely turnable thereon, means for automatically rotating the minute disk in unison with the spindle, means for manually rotating the disk independently of the spindle, an hour disk positioned adjacent the minute disk, a star gear cooperating with the hour disk and having twelve teeth formed thereon, and one of said teeth being larger than the remaining teeth to impart an added movement to the hour disk, and a pin carried by the minute disk and adapted to successively engage the teeth of the star gear.
8. In a mechanism of the character described, a main minute hand spindle, a minute disk freely turnable thereon, means for automatically rotating the minute disk in unison with the spindle, means for manually rotating the disk independently of the spindle, an hour disk positioned adjacent the minute disk, a star gear cooperating with the hour disk and having twelve teeth formed thereon, and one of said teeth being

larger than the remaining teeth to impart an added movement to the hour disk, a pin carried by the minute disk and adapted to successively engage the teeth of the star gear, 5 notches formed in the periphery of the respective disks, an alarm pallet, and a lever carried by the pallet normally engaging the periphery of the disks and adapted to release the alarm pallet when the notches in the 10 disks register with the lever.

9. In a mechanism of the character described, the combination with the main minute hand spindle, of a minute disk turnably mounted on the spindle, a ratchet gear secured to the spindle, pawls pivotally mounted on the minute disk and engaging said gear and forming a driving connection between the gear and the disk whereby the disk is rotated in unison with the spindle, said 15 ratchet gear having sixty teeth, a second ratchet gear turnably mounted on the spindle, said gear also having sixty teeth, but said teeth being positioned intermediate the teeth on the first-named ratchet gear, pawls mounted on the minute disk and engaging the second-named ratchet gear to form a 20 driving connection between the disk and the gear, an alarm dial graduated into hours and minutes, a spindle extending through the dial and having a minute hand secured thereto, a sleeve turnably mounted on the spindle and having an hour hand secured thereto, a dial gear train connecting the sleeve and the second named spindle, and means for imparting rotary movement from said second named spindle to rotate the 25 second named ratchet gear.

10. In a mechanism of the character described, the combination with the main minute hand spindle, of a minute disk turnably mounted on the spindle, a ratchet gear secured to the spindle, pawls pivotally mounted on the minute disk and engaging 30 said gear and forming a driving connection between the gear and the disk whereby the disk is rotated in unison with the spindle, said ratchet gear having sixty teeth, a second ratchet gear turnably mounted on the spindle, 35 said gear also having sixty teeth, but said teeth being positioned intermediate the teeth on the first-named ratchet gear, pawls mounted on the minute disk and engaging the second-named ratchet gear to form a 40 driving connection between the disk and the gear, an alarm dial graduated into hours and minutes, a spindle extending through the dial and having a minute hand secured thereto, a sleeve turnably mounted on the spindle and having an hour hand secured thereto, a dial gear train connecting the sleeve and the second named spindle, and means for imparting rotary movement from said second named spindle to rotate the 45 second named ratchet gear.

PAUL S. LUTTRELL.
